UNITED STATES PATENT OFFICE.

ROY M. BAKER, OF CHISHOLM, MINNESOTA.

LOADING MACHINE.

Application filed October 17, 1925. Serial No. 63,109.

My present invention relates generally to loading machines, and more particularly to a loading machine primarily intended for the handling of bulk materials such as ore, sand, gravel and the like, in mines and underground passages where space is limited and the head room inadequate for the use of the ordinary material used upon the surface for a similar purpose.

10 The primary object of my present invention is the provision of a machine or apparatus of this character adapted for control and actuation by a single operator, which will be simple and inexpensive, which will 15 be strong and durable, and which will be effective and efficient for the intended purposes.

With the above general objects in mind my invention proposes a readily portable 20 machine in which an extensible and retractable boom is pivoted at its inner end adjacent to the base of a turnable mast or upright, the boom in its retracted position being of either the same or less height than the 25 mast when raised to vertical position, and being of not substantially greater height in this position, including the bucket carried by the outer portion of the boom.

The foregoing and other objects of my 30 invention together with the resulting advantages thereof may be readily understood by reference to the accompanying drawings, illustrating the invention and forming a part of this specification, and wherein,

35 Figure 1 is a side elevation of my improved apparatus.

Figure 2 is a top plan view thereof.

Figure 3 is a transverse vertical section therethrough taken substantially on line 40 3-3 of Figure 1.

Figure 4 is an enlarged sectional side view of the outer end of the boom and the bucket carried thereby.

Figure 5 is a detail transverse section 45 taken on line 5-5 of Figure 4.

Figure 6 is a detail top plan view and partial section of the boom.

Figure 7 is a detail transverse section taken on line 7-7 of Fig. 6.

50 Figure 8 is a detail section through the boom controlling mechanism taken on line 8-8 of Figure 3.

Figure 9 is a detail section through the mast controlling mechanism taken on line

55 9-9 of Figure 3.

Figure 10 is a detail sectional side view illustrating a modified form of bucket.

Figure 11 is a top plan view of the same, and

Figure 12 is a transverse section taken 60 on line 12-12 of Figure 10.

Referring now to these figures and particularly to Figures 1 to 9 inclusive showing the preferred embodiment of my invention, I provide an apparatus including a 65 horizontal frame or platform 15 preferably mounted on flanged wheels 16, so that the apparatus as a whole may be easily and conveniently transported upon mine tracks 17. As seen especially in Figure 2, the platform 70 15 is rectangular and has pivotally connected braces 18 extending from its corners for connection by spikes 19 or the like to the track ties 20, as it is obvious that the apparatus as a whole must in use be effectively braced against lateral and longitudinal tilting.

Rising from the platform 15 and securely anchored thereto in the manner best shown in Figure 3 is a solid post 21, and 80 around this post the lower portion of a cylindrical upright mast 22 is journaled. The mast 22 has a lower gear wheel 23, and below said gear wheel 23 it rests upon an anti-friction bearing 24, facilitating its 85 rotational adjustment on the bearing post 21.

Engaging the gear 23 is a second smaller gear 25 secured upon the lower portion of a vertical shaft 26, whose lower end is stepped in a bearing 27 on the platform 15. The upper end of shaft 26 extends into a gear box 28 mounted in elevated position upon upright supporting beams 29, wherein the shaft has fixed thereto a bevel gear 30. Within the gear box 28 is a small motor 31, whose shaft 95 is connected by gears 32 to a clutch shaft 33, the latter having thereon two spaced apart and oppositely facing bevel gears 34 and 35 engaging gear 30 at diametrically opposite points. These gears 34 and 35 have 100 clutch faces 36 opposite one another for engagement by the similarly faced opposite ends 37 of a clutch member 38 splined on the shaft and adapted to be shifted by a lever 39, whose handle end 40 projects exteriorly of the body. In this way the rotation of the mast 22 and the direction of such rotation may be easily controlled by the operator on the platform 15.

Secured thereto immediately above the 110

gear wheel 23, the mast 22 has an outstanding bracket 42, and this bracket has opposing upstanding ears 43. Through these ears 43 a pivot bolt 44 extends, and also projects through the side members of the inner end or head 45 of the boom, or rather the body of the boom. The boom consists of two portions, an inner or body portion comprising the inner head 45, an outer head 46 and a series of tubular guide members 47 between these heads, and an outer portion or extension having a head 48 and a series of guide rods 49, which are slidable in the guide members 47 through the head 46. The body 10 of the boom has moreover a cylinder 50 to the opposite ends of which air or fluid pressure pipes 51 and 52 are connected in practice. The cylinder has therein a piston whose rod 53 is connected to the head 48 20 of the boom extension whereby the latter by suitable control of the supply of air or fluid through pipes 51 and 52 may be moved outwardly to the retracted position.

The upper end of the mast 22 is slotted 25 and has mounted therein a guide pulley 54, over which the boom controlling cable 55 is extended. The outer end of this cable is securely attached to the outer head 46 of the body of the boom by a member 55^a, while the inner end is extended around a winding drum 56 in a casing 57 attached to the mast as plainly seen in Figure 3. The drum 56 is controlled by a brake 58 actuated by a 30 brake lever 59, and the drum is mounted on the shaft 60 of a motor 61, also within the casing 57 as seen by a comparison of Figures 2 and 8.

As seen in Figures 1, 4 and 5 in particular, a clam shell bucket is employed, this bucket 40 having relatively movable sections 62 pivoted on a cross bar 63, which is rigidly connected to the lower ends of spaced curved supporting arms 64. This shaft has secured to its central portion an upright U-shaped frame 65, between the upper ends of which a cylinder 66 is fixed.

To the bucket sections the lower outer ends of a pair of connecting links 67 are pivoted at 68. The upper inner ends of these 50 links are movably connected to the ends of a cross-shaft 69 parallel with and above the bar 63. Centrally between the ends the shaft 69 is connected to the lower end of a piston rod 70, whose upper end is connected 55 to a piston 71 in the cylinder 66. To the opposite ends of the cylinder air or fluid pipes 72 and 73 are connected, and it is obvious that when the piston 71 is forced 60 downwardly the bucket sections 62 will be closed as indicated in dotted lines in Fig. 4, and that when the piston is forced upwardly 65 the bucket sections will move to the open position shown in full lines in said figure.

Instead of the clam shell bucket just above described, I may employ a scoop bucket 74 and the boom may then be raised during

of rectangular form as shown in the modification, Figures 10, 11 and 12. This bucket will have a filling lip 75 at one side of its open end, and will have at its opposite end a pivoted dumping door 76 hinged at 77 70 and normally latched by a spring latch member 78 slidable on the door and engageable with a keeper 79 depending from one of the bucket walls. To this latch member a flexible connection 80 is connected through a 75 lever 81, and by pulling this connection the latch member may be withdrawn and the door permitted to drop, with the parts in the dotted line position of Figure 10.

The bucket 74 is supported as a whole in 80 supporting arms 82 extending from the extension head 48^a of the boom, and to these arms 82 the bucket is pivotally connected at its sides as at 83, so it may swing from a horizontal loading position as shown in full lines in Figure 10 to a vertically dumping position shown in dotted lines. In utilizing this scoop bucket the outer head 46 of the boom has an angular lug 84 positioned for engagement by a hook 85 carried by the 90 bucket, when the boom is in vertical position and the boom extension is retracted. Thus when the boom is lowered the bucket will be held from swinging to a vertical position and thus supported for proper lowering 95 movement to the ground, until the extended boom is shifted outwardly to load the bucket.

In the operation of the apparatus with the bucket of Figures 10, 11 and 12, the operator first lowers the boom with the parts in the full line position of Figure 10 and then shifts the boom extension outwardly so as to force the open end of the bucket into the material to be loaded. The boom is then raised slightly and the extension is retracted after which the boom is elevated to nearly a vertical position, the mast turned to swing the boom around to the rear of the apparatus and then the boom lowered and the extension shifted outwardly to the car or other point where the material is to be dumped. The connection 80 is then pulled and the door 76 released so that the load drops. The boom is then raised and the extension retracted and hook 85 engages lug 84, as in Figure 10. The mast is then again turned so that the boom swings to a forward position and the boom is then lowered. During the last lowering of the boom preparatory to another loading operation, the door 76 will swing by gravity to closed and latched position.

In the use of the apparatus as shown in Figures 1 to 9 inclusive, the boom is raised and the boom extension shifted outwardly, and the bucket sections 62 actuated to the open position before the boom is lowered so that the open bucket is on the load. The bucket sections are then closed on the load 120 and the boom may then be raised during

which the boom extension is retracted. The mast is then rotated through 180 degrees and the boom lowered and its extension shifted outwardly. The bucket is then opened, permitting the load to dump after which the boom is raised, the extension retracted and the mast rotated so that the parts return to the loading position.

It is obvious from the foregoing that my invention presents a construction and arrangement of parts which readily carries out the objects first above stated and which promotes strength and durability in addition to effectiveness and efficiency in operation.

15 I claim:

The combination in a loading machine of

a wheeled frame, a mast rotatable thereon and a boom pivoted at the base of said mast, said boom comprising a pair of tubular guides and rigid heads connecting the 20 guides, an extensible frame comprising a head and reciprocable rods in said guides, a cylinder supported between said guides, a rod on the head of the extensible frame and a piston for said rod in the cylinder, means 25 for introducing motive fluid at opposite sides of said piston, and a loading bucket carried by the extensible frame.

In testimony whereof I have affixed my signature.

ROY M. BAKER.
